CHILD'S SHOE COVERING

Catherine Joseph, Santa Barbara, Calif., assignor of one-tenth to Gadget-Of-The-Month Club, Inc., North Hollywood, Calif., a corporation of California

Filed June 29, 1960, Ser. No. 61,146

Term of patent 14 years

(Cl. D7—7)

FIG. 1 is a side elevation view of a child's shoe covering showing my new design.

FIG. 2 is a rear elevational view.

FIG. 3 is a top plan view.

The essential features of my design reside in the portions shown in full lines on the drawing.

I claim:

The ornamental design for a child's shoe covering, substantially as shown and described.
